CONRAD F. BIRGBAUER, OF DETROIT, MICHIGAN

LAPPING DEVICE

Application filed March 15, 1930. Serial No. 436,190.

The main objects of this invention are to provide improved lapping and grinding devices on which granular abrasives such as diamond dust are used; to provide a device 5 of this kind which has a plurality of closely held together convolutions between which abrasive material is confined; to provide abrasive material between adjacent convolutions which have aligned corresponding surfaces 10 forming a working surface in conjunction with the abrasive material; to provide releasable means for retaining said convolutions in a compressed position so as to allow the convolutions to be expanded for renewing the deposits of abrasive material; to provide 15 films of abrasive material which extend inwardly from the working surface of the device a substantial distance so as to maintain a uniform cutting capacity as the working surface wears during operation; and to provide deposits of abrasive material in crevices between adjacent turns of a substantially soft, metal coil so that as the abrasive material is dislodged during operation 20 it is embedded in the metal.

An illustrative embodiment of my invention is shown in the accompanying drawing, in which

Fig. 1 is a side elevation of a lap embodying my invention.

Fig. 2 is a side elevation, partly in section, showing part of the lapping device in an expanded position.

Fig. 3 is a central, vertical section showing a modified form of my invention.

Fig. 4 is a central section showing a further development of my invention.

Fig. 5 is a plan view showing a part of the device illustrated in Fig. 4 in an expanded position.

Fig. 6 is a fragmentary section taken on the line 6—6 of Fig. 5.

In the form shown, the lap has a shank 1 having a driving tang 2 on one end which 45 may be engaged between jaws of a rotary drive mechanism (not shown). Formed on the other end of the shank 1 is an enlarged cylindrical head 3 having a substantially flat radial extremity or shoulder 4, beyond which 50 a stem 5 of reduced diameter extends. Seat-

ed on the stem 5 is a helical coil 6 which has a central passage 7 for receiving the stem 5. The diameter of the central passage 7 may be slightly greater than the diameter of the stem 5 and the outer diameter of the coil 6 is 55 preferably greater than the diameter of the cylindrical head 3, thus causing the outer periphery of the coil to protrude the periphery of the head 3.

The helical coil 6 is preferably formed of 60 spring bronze or other suitable resilient material which is somewhat ductile, such as aluminum, copper and brass. Cast iron, steel, or other comparatively hard metals may be employed for this purpose if desired. 65

This coil is formed of a flat bar or strip of metal which is wrapped helically on an arbor with the outer surfaces of each convolution in alignment with each other. The pitches of the convolutions are substantially 70 uniform and the sides of the convolutions may be finished so as to allow the adjacent sides thereof to be drawn into close proximity of each other when the coil is compressed.

A film of abrasive material 8, preferably 75 diamond dust, is provided between adjacent convolutions of the coil 6. Any other suitable material such as carborundum or emery of granular form may be used. The abrasive, in a vehicle such as oil, is preferably smeared or otherwise applied upon corresponding 80 sides of all of the convolutions while the coil is in an expanded position. Glue or other adhesive substances may be used in place of the oil to secure the abrasive in place while 85 the device is being assembled. The coil 6 is then drawn down or compressed to the shape shown in Fig. 1 and a head 9 is formed on the outer extremity of the stem 5 so as to permanently retain the coil 6 in a compressed 90 condition, thus retaining the abrasive between each turn of the coil in place, and causing at least part of the abrasive to be embedded in such surfaces.

In the form shown in Fig. 3, the lapping 95 tool comprises a shank 1' having a head 3' which is provided with a central aperture in which a stem or bolt 5' is mounted. Seated on the bolt 5' is a helical coil 6' having a film of abrasive material 8' between its adjacent 100

convolutions. The coil 6 is releasably held in a compressed position between the extremity of the head 3' and a washer 10 by a bolt 11. When the bolt 11 is removed the 5 spring 6' expands permitting a new film or deposit of abrasive material to be applied on the side of the convolution.

In the form of my invention shown in Figs. 4, 5 and 6, a flat spiral coil 12, preferably of spring bronze, is seated in a cylindrical cup 13 which is mounted on the end 10 of a shank 14 by a screw 15 having a countersunk head. The screw 15 extends centrally through the coil 12, retaining the latter 15 under compression within the cup 13. A film 20 of abrasive material is located between adjacent convolutions of the coil and the abrasive material is exposed at the ends of the convolutions which are arranged substantially in alignment with each other.

In each form of my invention, the aligned outer surfaces of the convolutions and the exposed areas of the abrasive films provide working surfaces which have fast cutting capacities. When the coils are formed of comparatively soft metal, the particles of abrasive which are dislodged from the crevices between the adjacent convolutions become embedded in the exposed surfaces thereof 30 and remain in a useful position. It may here be noted that in some instances grains or particles of abrasive independent of the films between the turns, may be rolled or otherwise worked into the cutting surface of the device to enhance its cutting value.

Although but several specific embodiments of this invention have been herein shown and described, it will be understood that various changes including the size, shape and arrangement of parts may be made without departing from the spirit of my invention, and it is not my intention to limit its scope other than by the terms of the appended claims.

I claim:

1. A lapping tool comprising a coil of substantially rigid material, and abrasive substance between adjacent convolutions of said coil.

2. A lapping tool comprising a coil of substantially soft metal material, and diamond dust clamped between adjacent convolutions of said coil.

3. A lapping device comprising a plurality of convolutions of metal each having a surface in alignment with a corresponding surface of each of the other convolutions, and abrasive material between adjacent convolutions and exposed at said aligned surfaces.

4. A lapping device comprising a plurality of convolutions of metal each having a surface in alignment with a corresponding surface of each of the other convolutions, and a film comprising granular abrasive material and a vehicle between adjacent convolutions and exposed at said aligned surfaces.

5. A lapping tool comprising a coil of metal material, an abrasive substance between adjacent convolutions of said coil, and means engaging the respectively opposite ends of said coil for retaining the same under 70 compression.

6. A tool of the class described comprising a shank, a support on said shank, a metal strip helically formed about said support, and abrasive material confined between adjacent 75 turns of said metal strip.

7. A tool of the class described comprising a shank, a support on said shank, a metal strip coiled on said support, and abrasive material confined between adjacent turns of said 80 metal strip.

8. A tool of the class described comprising a shank adapted to rotatably connect said tool to a driving member, a plurality of superimposed convolutions secured on said shank, 85 layers of abrasive material between adjacent convolutions, and means for releasably clamping said convolutions together.

9. A lapping tool comprising a shank, a helical coil on the end of said shank, successive turns of said coil having peripheral surfaces in alignment with each other, abrasive material between adjacent sides of said turns and exposed at the outer periphery of said coil, and means for compressing said 90 coil to provide a substantial continuous working surface on the outer periphery thereof.

10. A lapping tool comprising a support, a stem on said support, a resilient member coiled about said stem, a film of diamond dust located between adjacent turns of said coil, and releasable means on said stem for retaining said resilient member under compression so as to confine said diamond dust between 100 said convolution and to form a substantially 105 continuous working surface on said coil.
